US0D1114262S

(12) **United States Design Patent** (10) **Patent No.:** **US D1,114,262 S**
Chen (45) **Date of Patent:** **** Feb. 17, 2026**

(54) **HEARING AID**

(71) Applicant: **Hetaida Technology Co., Ltd.**,
Dongguan (CN)

(72) Inventor: **Zhenguang Chen**, Dongguan (CN)

(73) Assignee: **HETAIDA TECHNOLOGY CO., LTD.**,
Dongguan (CN)

(**) Term: **15 Years**

(21) Appl. No.: **29/983,073**

(22) Filed: **Jan. 9, 2025**

(51) LOC (15) Cl. **24-99**

(52) U.S. Cl.

USPC **D24/174**

(58) **Field of Classification Search**

USPC D24/174, 173, 175, 106, 133, 141;

D14/205, 223

CPC H04R 25/02; H04R 1/1075; H04R 1/1016;

H04R 1/1008; H04R 2225/021; H04R

2225/023; H04R 2225/025; H04R 25/604
